5 Claims. (Cl. 252—106)

1

This invention relates to novel and particularly advantageous washing and disinfecting compositions.

All hitherto known and usual compositions employed to disinfect the human skin are attended by a great disadvantage in that their action is greatly impaired by the presence of albumin, a phenomenon which is manifested by precipitation of dissolved albumin.

Since the excitors of disease are generally surrounded by albumin vessels which bind the greater part of the disinfectant employed, the action of such compositions on the excitors is often very questionable. Moreover, the property of the said compositions of becoming bound to albumin has a disadvantageous effect on the human skin since the keratin of the skin also reacts with the disinfecting composition and is thus modified. Treatment of the skin with such compositions therefore, results in the most favourable cases in roughening and cracking of the skin.

The surprising discovery has now been made that it is possible so to influence disinfecting compositions having very great bactericidal activity, by adding other substances, that the reaction with albumin is suppressed while the anti-bacterial activity is maintained. At the same time a further fact was established, which can also be turned to advantage, namely that the substances which must be added for the aforesaid purpose and which achieves the aforesaid effect, are substances having good washing and foaming properties.

According to the invention, it has thus been possible to provide new compositions which constitute both washing and disinfecting agents and are substantially superior to all known compositions of this type. The washing and disinfecting compositions according to the invention consist of a mixture, preferably in a weight ratio of about 2:1 to 9:1, of a washing component composed of a salt of an organic or inorganic acid with an amino acid which, in addition to an aliphatic radical containing 10 to 18 carbon atoms, contains at least 2 and preferably 3 or more basic nitrogen atoms, and at least one carboxyl group, and of a disinfecting component composed of a salt of an organic or inorganic acid with an amino acid which in addition to at least 2 aliphatic radicals containing 6 to 10 carbon atoms contains at least 2 preferably 3 or more basic nitrogen atoms and at least one carboxyl group, preferably, octyl di(aminoethyl)-octylamino-acetic acid-hydrochloride or di(octyl-aminoethyl)-amino-acetic acid-hydrochloride.

2

The washing and disinfecting compositions according to the invention may also consist of mixtures containing more than two of the aforesaid components.

The constituents on which the mixtures according to the invention are based can be produced by various processes, and advantageously, for example, by the process described in German patent application G. 110,055 IVC/12q of the same applicant dated October 24, 1944. Particularly suitable washing components are, for example, compounds of the following formula

15 wherein R=C₁₆H₃₃, or the acetate or lactate of this amino acid.

The substances which preferably come into consideration as disinfecting components are:

Octyl-di(aminoethyl)-octylamino-acetic acid-hydrochloride:

25 Di(octylaminoethyl)-amino-acetic acid-hydrochloride:

The said two substances when used alone, are detrimentally effected in their anti-bacterial ac-

30 tivity owing to the presence of albumin, but when used in admixture with the above-mentioned washing components, neither precipitation nor deterioration occurs with albumin. A solution of the two components in a physiological cooking

35 salt solution in such concentration that both gram-positive and gram-negative bacteria are destroyed within 5 minutes by this solution, has exactly the same action as an equivalent solution prepared with undiluted blood serum instead of physiological cooking salt solution. A comparative experiment carried out under the same conditions with known usual disinfecting compositions showed considerable reductions in value in the presence of serum, for

40 45 Alkyl - dimethyl - benzylammonium chloride (Zephirol)

Chlorobenzylate of a higher alkylamide of di-methylamino-acetic acid (Quartamon)
p-Chloro-m-oresol and p-chlorxylenol in fat
50 soap (Sagrotan)

Even persons having a particularly sensitive skin can withstand, without any irritation whatever, washing of the hands several times daily over a period of weeks with the washing and dis-

infecting compositions according to the invention. The cleansing and foaming action can be regarded as very good, so that even firmly adhering dirt can readily be removed so as to leave all crevices clean. After washing with the compositions according to the invention, a pleasant soft feeling remains on the skin. Finally, the neutral to weakly acid reaction and the complete stability against lime of the compositions according to the invention may also be mentioned as a further advantage.

By reason of the combination of all these favourable properties, the composition according to the invention constitutes a particularly valuable advance in the development of the art of disinfection.

Example 1

100 parts of a 30% aqueous solution of a compound corresponding to the formula

are mixed with 50 parts of a 30% aqueous solution of a compound corresponding to the formula

and diluted with 150 parts of water.

A washing and disinfecting medium is obtained which has a very strong bactericidal action and good foaming and cleansing properties. The solution produces no precipitate with albumin.

Example 2

100 parts of the first solution mentioned in Example 1 are mixed with 50 parts of a 30% solution of a compound corresponding to the formula

and diluted with water.

Example 3

An aqueous solution is prepared which contains 10% of a compound of the formula

4% of a compound of the formula

1% of a compound of the formula

I claim:

1. A washing and disinfecting composition comprising a mixture of 2 to 9 parts by weight

of an acid addition salt of a polyethylene polyamine compound selected from the group consisting of diethylene triamine and triethylene tetramine carrying one alkyl substituent containing 12 to 16 carbon atoms on one of the terminal amino groups and 1 to 2 $-\text{CH}_2\text{COOH}$ substituents on the other terminal amino group as a washing component and 1 part by weight of the hydrochloride of diethylene triamine carrying an octyl substituent on each terminal amino group and 1 $-\text{CH}_2\text{COOH}$ substituent on one of the nitrogen atoms thereof as a disinfecting component.

2. A washing and disinfecting composition comprising a mixture of 2 to 9 parts by weight of an acid addition salt of

and 1 part by weight of the hydrochloride of diethylene triamine carrying an octyl substituent on each terminal amino group and 1 $-\text{CH}_2\text{COOH}$ substituent on one of the nitrogen atoms thereof as a disinfecting component.

3. A washing and disinfecting composition comprising a mixture of 2 to 9 parts by weight of

and 1 part by weight of

4. A washing and disinfecting composition comprising a mixture of 2 to 9 parts by weight of

and 1 part by weight of

5. A washing and disinfecting composition comprising a mixture of

$\text{C}_{16}\text{H}_{33}.\text{NH}.\text{CH}_2.\text{CH}_2.\text{NH}.\text{CH}_2$

$\text{CH}_2.\text{N}.\text{(CH}_2.\text{COOH})_2.\text{HCl}$

and

in a proportion of about 10:4:1 by weight.
